UNITED STATES PATENT OFFICE.

PAUL PONDORF, OF GOSSNITZ, GERMANY, ASSIGNOR TO THE FIRM MASCHINEN- & METALLWARENFABRIK G. M. B. H., OF BERLIN, GERMANY.

METHOD AND APPARATUS FOR ROLLING IN THE NECK IN PRESS-BUTTON PARTS OR THE LIKE.

1,417,199.

Specification of Letters Patent. Patented May 23, 1922.

Application filed January 15, 1921. Serial No. 437,635.

To all whom it may concern:

Be it known that I, PAUL PONDORF, a citizen of the German Republic, and a resident of Gossnitz, Saxony, Germany, have invented certain new and useful Improvements in Methods and Apparatus for Rolling In the Neck in Press-Button Parts or the like (for which was filed application S. 51,977 I/7c in Germany on January 9, 1920, by Sylbe & Pondorf, with my knowledge and consent), of which the following is a specification.

The known clasp- or press-buttons consists of two parts, the resilient lower part, which is provided with a head and a neck and which is pressed into the lower part, where the head is firmly held by the spring portions of said lower part. The parts of the press buttons are drawn in groups, then cut out and finished by special machinery. In the latter the upper parts pass between rotating disks, whereby the neck is rolled in and the head is formed. This method however has the disadvantage, that the buttons must be fed to the machine by hand or by special, automatically acting devices, whereby much waste is produced.

This drawback is successfully obviated by the subject-matter of the invention in such a manner, that the necks of the press-button parts are rolled in by periodically opening and closing claws, which turn with vertically reciprocating spindles, the rolling being effected while the button-parts are still in the sheet-metal strip, whereby the feeding of single press-button parts, which are independent of each other, to the tools effecting the rolling in of the neck is avoided.

In order to further elucidate the method, the basic principles of which have already been indicated in the foregoing preamble, the machine or apparatus for performing said method will be more fully explained hereinafter. Said apparatus is illustrated in the accompanying drawings, in which

Fig. 1 shows the apparatus partly in front view and partly in vertical section.

Fig. 2 is plan view of Fig. 1.

Fig. 3 is a side-view of a detail of construction, while

Fig. 4 represents a side-view of the machine as a whole.

Figs. 5 and 6 each shows a vertical section

through the claw-head and its conical bearing-sleeve at the lowered position of the 55 claw-head-spindle and closed position of the claws and at the raised position of the claw-head-spindle and open position of the claws.

Figs. 7, 8 and 9 each shows a section through the lower button-part before and 60 after the rolling and after the stamping.

As it can be seen from the drawings, the apparatus consists of the frame 1, in which the slide 2 is guided at 3 in such a manner, that it can be vertically displaced (Fig. 2). 65 To the frame 1 on each side of the same two arms 4, 5 are rigidly connected, in which the two guide-rods 6, 6 are vertically shiftably guided. To these guide-rods the plate 7 is secured by means of its eyes 8, 8. The 70 guide-rods 6, 6 are surrounded by spiral springs 12, the upper ends of which press against the arms 4, 4, while their lower ends engage with the eyes 8, 8 of the plate 7, said springs having the tendency, of always 75 pressing downwardly the plate 7.

On the frame 1 the two-armed lever 10 is pivotally mounted by means of the pivot-bolt 9, the arm 10 of said lever being under the influence of a (not illustrated) cam-disk, while the other arm 11 engages with the lower side of the plate 7 and at the upward oscillating movement displaces upwardly said plate with the guide-rods 6, 6, 80 in opposition to the tension of the springs 12. 85

In the slide 2 one or more spindles 13 are rotatably mounted, the number and arrangement of which is in accordance with the buttons 14' prepared in the sheet-metal strip, 14. All spindles 13 are in operative connection 90 with each other by means of gear wheels 15 of equal size, secured to said spindles and by means of the intermediate gear wheel 17 which is rotatably mounted on the pin 16, so that when the spindle 13' is rotated by 95 means of its pulley 18 from a belt drive, said rotation is also transmitted to the other spindles.

The sleeves 19, through which the spindles 13 pass freely slidably, are mounted on the 100 plate 7 in such a manner, that they can rotate in unison, each of these spindles being provided below the plate 7 with a conical circumferential face 20. At their lower ends the spindles 13 terminate in claw-heads 21, 105 to each of which two claws 23 are pivotally

secured by means of the pivot pins 22. The claw-heads are provided with engaging parts 24, directed towards the spindle axes and serving to roll in the button neck; in 5 the lowermost position of the spindle 13 the inwardly directed arms 25 of the claws 23 project somewhat beyond the conical circumferential faces 20 of the sleeves 19.

Each of the spindles 13 is provided with 10 a collar 26, supporting the slide 2. When the plate 7 is lifted by the oscillating movement of the lever 10, 11, the sleeves 19 strike against the collars 26 and lift the spindles 13 together with the slide 2.

15 For the sake of completeness it may be mentioned further that the reference numerals 27 indicate the hollow cylindrical punching-knives arranged in the same groups as the spindles 13, said punching-knives being rigidly connected to the plate 28 and being guided with their lower ends in corresponding bores of the punching-device 35. Plate 28 by means of pins 28' may slide up and down in slots of the 20 vertical bars 30' by which plate 28 is suspended from plate 30. In the bores of the punching knives the stamping-dies 29, which are rigidly connected to the plate 30, are 25 slidably mounted. To the plate 30 arms 32 are pivoted by means of pivot-pins 31, which arms with their inwardly directed projections 33 are supported on plate 28, whereby the plate 30 during its downward movement 30 with the plate 28 is held in a certain distance 35 from the latter. At their lower ends 34 the arms 32 are beveled, so that said arms, when striking, at their downward movement, against a beveled edge of the die-frame 35, with the beveled faces 34 will slide off of 40 said die-frame, whereby the arms 32 with the projections 33 are drawn off from the plate 28, and the latter is released thereby.

Below the punching-device the matrix-frame 36 is arranged, in which the matrices 45 37 are mounted, the number and arrangement of which corresponds to that of the stamping-dies 29.

The operation of the device is as follows: The sheet-metal strip 14 with the prepared 50 press-button parts 14' is intermittently advanced in the direction of the arrow 38 (Fig. 1). Thereby the press-button parts are moved under the claw-heads 21 (Fig. 1), which are in the raised position according to 55 Fig. 6 and on account of the rotation of their spindles are held in open position by means of the centrifugal force action upon the claws 23. At this moment the lever arm 11 moves downwardly and releases the plate 7, 60 which latter is pressed downwardly into the position shown in Figs. 1 and 4 by means of the spiral springs 12. Simultaneously the slide 2 with the spindles is lowered, until the latter engage with the little heads 14'' of the 65 press-button parts (Fig. 4). As the plate 7

with the sleeves 19 moves for a certain distance further downwardly than the spindles 13, the conical circumferential faces 20 of the sleeves act upon the arms 25, whereby the same are forced away from each other and the claws 25 are caused to approach each other, until they are in close engagement with the neck of the press-button part. As the claws are rotating with the spindles they will roll in the press-button necks. On account of the upward oscillating movement of the lever arm 11 the sleeves 19 move again upwardly, which results in an opening of the claws. The sleeves 19 then strike against the collars 26 of the spindles and lift the 80 same with the slide 2, whereupon the sheet-metal strip is again advanced.

The press-button parts with the rolled in 85 necks are finally moved under the punching device 35 and are here cut out by means of the punching-knives 27, moving downwardly together with the stamping-dies 29 (Fig. 8). The latter, which then move still farther downwardly, press the cut out press-button parts 14' through the downwardly reduced 90 matrices 37, whereby the press-button parts receive the desired shape, which is illustrated in Fig. 9.

Having thus particularly described the 95 nature of my invention, what I claim as new and desire to secure by Letters Patent of the United States is:

1. Apparatus for rolling in the necks in 100 press-button parts comprising in combination a vertically reciprocable slide, a plurality of spindles rotatably mounted in said slide, means to rotate the spindles, a claw-head provided at the lower end of each of said spindles, claws pivoted to each of said claw-heads and adapted to effect in closing 105 position the rolling in of the button-necks, downwardly conically reduced sleeves, rotatably mounted in a vertically reciprocable plate and loosely surrounding said spindles, said sleeves being adapted to engage with 110 said claw-heads and to thereby effect the closing of the claws, pivoted to said claw-heads, a two-armed lever, adapted to be oscillated and to thereby effect the upward-movement of said plate, and spiral springs, 115 adapted to effect the downward movement of the same.

2. Apparatus for rolling in the necks in 120 press-button parts, comprising in combination a vertically reciprocable slide, a plurality of spindles, rotatably mounted in said slide, means to rotate the spindles, collars secured to said spindles and adapted to carry said slide, a claw-head provided at the lower end of each of said spindles, claws pivoted 125 to each of said claw-heads and adapted to effect in closing position the rolling in of the button-necks, downwardly conically reduced sleeves, rotatably mounted in a vertically reciprocable plate and loosely surround- 130

ing said spindles, said plate engaging at the upward movement with the collars of said spindles and thereby lifting said spindles and said slide, a two-armed lever engaging with the lower side of said plate, said lever being adapted to be oscillated and to thereby effect the upward-movement of said plate and spiral springs arranged on arms of the

machine frame and adapted to effect the downward movement of the plate. 10

In testimony whereof I affix my signature in presence of two witnesses.

DR. PAUL PONDORF.
